US00D991564S

(12) **United States Design Patent** (10) Patent No.: **US D991,564 S**
(45) Date of Patent: **** Jul. 4, 2023**

(54) **ELECTRIC DRY SHAVER BRUSH**

(71) Applicant: **Braun GmbH**, Kronberg (DE)

(72) Inventors: **Bernhard Sikora**, Kelkheim (DE);
Wolfgang Stegmann, Frankfurt (DE)

(73) Assignee: **Braun GMBH**, Kronberg (DE)

(**) Term: **15 Years**

(21) Appl. No.: **29/782,857**

(22) Filed: **May 10, 2021**

Related U.S. Application Data

(62) Division of application No. 29/682,831, filed on Mar. 8, 2019, now Pat. No. Des. 922,684.

(30) **Foreign Application Priority Data**

Jan. 24, 2019 (WO) 970012457
